CLOTHESLINE SUPPORT

Clair Madigan, San Francisco, Calif., assignor
of one-half to Gustav Anderson, San Francisco,
Calif.

Application June 8, 1940, Serial No. 339,545

4 Claims. (Cl. 211—119.06)

The present invention relates to new and useful improvements in clothesline supports and has for its primary object to provide, in a manner as hereinafter set forth, novel means for supporting one end of a clothesline for permitting said clothesline to be conveniently raised and lowered to facilitate hanging clothes and other articles thereon and removing said clothes or other articles therefrom.

Other objects of the invention are to provide a clothesline support of the aforementioned character which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation, illustrating a clothesline support constructed in accordance with the present invention.

Figure 2 is a view in horizontal section, taken substantially on the line 2—2 of Fig. 1.

Figure 3 is a horizontal section through the swinging track, taken substantially on the line 3—3 of Fig. 1.

Figure 4 is a view in front elevation, showing the cleat and eye which are brought into use when the support is in folded position.

Figure 5 is a fragmentary sectional view through an intermediate portion of the longitudinally extensible arm, taken substantially on the line 5—5 of Fig. 1.

Figure 6 is a detail view in horizontal section, taken substantially on the line 6—6 of Fig. 4.

Figure 7 is a sectional view through the upper portion of the device, taken substantially on the line 7—7 of Fig. 1.

Figure 8 is a view in vertical section, illustrating the mounting of the pulley on the upper bracket.

Referring now to the drawings in detail, it will be seen that the embodiment of the invention which has been illustrated comprises upper and lower brackets 1 and 2, respectively, which are mounted on a suitable support 3. Pivotedly mounted for swinging movement in a vertical plane on the upper bracket 1 and depending therefrom is a tubular track 4.

Pivotedly mounted for swinging movement in a vertical plane on the lower bracket 2 is a lon-

gitudinally adjustable arm which is designated generally by the reference numeral 5. The arm 5 comprises telescopically adjustable sections 6 and 7, the latter having pivotally mounted on its outer or free end portion a ring or loop 8 which is slidable on the track 4. The sections 6 and 7 are secured in adjusted position through the medium of a pin 9 removably mounted in said section 6. The pin 9 is insertable selectively in spaced openings 10 which are provided therefor in the section 7.

Slidably mounted on the track 4 is a carriage 11. Projecting from the carriage 11 is a hook 12 to which a pulley 13 on one end of a clothesline 14 is connected. The other end of the clothesline 14 is mounted in elevated position on a suitable support 15.

Also mounted on the upper bracket 1 is a pulley 16. A cable 17 is trained over the pulley 16 and has both ends secured to the carriage 11.

Mounted on the support 3 below the lower bracket 2 is a suitable cleat or button 18. Mounted below the cleat or button 18 on the support 3 is an eye 19. The reference numeral 20 designates a hook on the free end of the track 4 which is engageable in the eye 19 for releasably securing said track 4 in retracted or folded position.

It is thought that the operation of the device will be readily apparent from a consideration of the foregoing. Briefly, with one end of the clothesline 14 in lowered position, as illustrated in Fig. 1 of the drawings, the clothes and other articles may be conveniently mounted on said clothesline. When this has been done the carriage 11 is moved upwardly on the track 4 through the medium of the cable 17, thus elevating this end of the clothesline. The cable 17 is then wrapped around the cleat or button 18 for securing the clothesline in raised or elevated position. Then, by swinging the arm 5 upwardly to a substantially vertical position parallel to the support 3, the track 4 may be swung inwardly to folded position and secured by engaging the hook 20 in the eye 19, as suggested in dotted lines in Fig. 1 of the drawings. Of course, to lower the clothesline the foregoing operation is substantially reversed. By lengthening or shortening the adjustable arm 5 the distance that the track 4 may swing outwardly may be regulated as desired. In this manner the clothesline 14 may be kept tight at different elevations when in lowered position.

It is believed that the many advantages of a clothesline support constructed in accordance with the present invention will be readily under-

stood and although a preferred embodiment of the device is as illustrated and described, it is to be understood that changes in the details of construction and in the combination and arrangement of parts may be resorted to which will fall within the scope of the invention as claimed.

What is claimed is:

5. 1. A clothesline support comprising a track pivotally mounted for swinging movement in a vertical plane on a supporting structure, a carrier, for connection with one end of a clothesline, slideable on said track, an arm pivotally mounted for swinging movement in a vertical plane on the supporting structure and having its free end slidably connected to the track, and means for raising and lowering the carrier on the track.
10. 2. A clothesline support comprising a track pivotally mounted for swinging movement in a vertical plane on a supporting structure, a carrier, for connection with one end of a clothesline, slideable on said track, an arm pivotally mounted for swinging movement in a vertical plane on the supporting structure and having its free end slidably connected to the track, and means for raising and lowering the carrier on the track.
15. 3. A clothesline support of the character de-

scribed comprising vertically spaced upper and lower brackets mounted on a support, a pulley mounted on the upper bracket, a track pivotally mounted for swinging movement in a vertical plane on said upper bracket and depending therefrom, a carrier slideable on said track, means for connecting said carrier with one end of a clothesline, a cable trained over the pulley and having its ends connected to the carrier for raising and lowering said carrier, and an arm pivotally mounted on the lower bracket for swinging movement in a vertical plane and slidably connected to the track, said arm constituting means for limiting the swinging movement of the track in one direction.

4. A clothesline support comprising vertically spaced upper and lower brackets, a track pivotally mounted for swinging movement in a vertical plane on the upper bracket and depending therefrom, a carriage slideable on said track and adapted for connection with one end of a clothesline, means for raising and lowering the carriage, an arm pivotally mounted for swinging movement in a vertical plane on the lower bracket, said arm comprising a pair of telescopically adjustable sections, and a ring on the free end of the arm slideable on the track for connecting said track to the arm, said arm constituting means for limiting the swinging movement of the track in one direction.

CLAIR MADIGAN.
